UNITED STATES PATENT OFFICE.

CLAES RYDEN, OF CRANSTON, RHODE ISLAND, ASSIGNOR, BY MESNE ASSIGNMENTS,
TO UNIVERSAL WINDING COMPANY, OF BOSTON, MASSACHUSETTS, A CORPORATION
OF MASSACHUSETTS.

WINDING-MACHINE.

1,203,790.

Specification of Letters Patent.

Patented Nov. 7, 1916.

Application filed January 30, 1915. Serial No. 5,297.

To all whom it may concern:

Be it known that I, CLAES RYDEN, a citizen of the United States, residing at Cranston, in the county of Providence and State of Rhode Island, have invented certain new and useful Improvements in Winding-Machines, of which the following is a specification.

My invention relates to winding machines for winding electrical coils and particularly to machines of the type shown and described in United States Patent No. 1,184,268, granted to Max Helm April 6, 1915.

My present improvement is directed to the traverse-mechanism of the winding-apparatus and its object is to adapt the machine to wind coils by the improved system set forth in an application for patent for electrical coils and method of winding same filed concurrently herewith.

In the machine of the application for patent first referred to the traverse-mechanism comprises two reciprocating guides; one, the wire-guide, for depositing the conducting-material on the coil in concentric layers, and another, the thread-guide, for traversing the yarn or similar insulating-material diagonally or crosswise of the wire-windings. The two guides are operated simultaneously to traverse them longitudinally of the rotating winding-spindle with the wire-guide reciprocated at a relatively slow rate of speed while the thread-guide has a much faster rate of speed. Through the operation of this mechanism the wire or other conducting-material is deposited in overlying layers of close spirals while the yarn or other insulating-material is wound in layers partially separating the wire layers and arranged with the strands thereof intersecting the turns of the wire in each layer of the coil. In this way the insulating-material is caused to weave through the wire layers, over and under the separate turns of the wire, to bind the wire-windings in place and reinforce the whole structure of the coil. In winding coils according to this system it is the preferred practice to deposit the insulating-material with a longer traverse than that of the wire so that the yarn-windings will overlap the ends of the wire layers to build up washer-like abutments or closures at the ends of the coil. As set forth in my companion application Serial No. 5,296, filed Jan. 30, 1915, I have now devised a novel

and improved method of disposing the insulating-material at the ends of the coil to build up more secure and substantial abutments for supporting and protecting the ends of the wire layers. This improved system comprises essentially the winding on of more yarn at the ends of the coil than between the overlying layers of wire so that a more solid and compact abutment or end-closure is secured and a better reinforcing and insulating medium provided. To carry out this improvement in the method of winding as above described I have devised a means for imparting an additional reciprocating movement or series of short traverses to the guide for the insulating-material at each end of its primary or main traverse. That is to say, in my present improved arrangement of the traversing-mechanism for the yarn- or thread-guide, the latter is given several supplementary short traverses each time it reaches the end of its main traverse, and through this means the yarn is built up at a faster rate at the ends of the coil than between the layers of wire-windings. The manner and means for accomplishing this improvement are fully set forth in the following specification, illustrated by the accompanying drawings, in which like reference characters designate like parts.

In the drawings: Figure 1 is an elevation of a coil-winding machine, showing my improvements applied thereto; Fig. 2 is an end view of the same, part sectional on the line X—X of Fig. 1, and illustrating the arrangement of the traverse-guides for the wire and yarn; Fig. 3 is a view of one form of the traverse-cam for reciprocating the yarn- or thread-guide of the machine; Fig. 4 is a development of the periphery of said cam, illustrating the peculiar form of its guide-traversing groove; Fig. 5 shows a slightly modified form of traverse-cam; Fig. 6 is a development of the groove in the latter; Fig. 7 shows one strand of yarn wound on the tube or core α to illustrate its convolutions with the extra traverses at the ends of the main traverses, as effected by the cam shown in Figs. 3 and 4; Fig. 8 is a similar view showing one strand of yarn wound onto the core in a slightly different manner, as provided with a cam of the form shown in Figs. 5 and 6; Fig. 9 is a view of the nearly completed coil as wound on my

improved machine; and Fig. 10 is a view showing a few layers of yarn wound on the central, supporting core of the coil without any wire to illustrate one method of building up the end abutments of yarn-windings.

Referring first to Figs. 1 and 2, A designates the main frame of the machine provided at its top with bearings for the rotating winding-spindle *b*. The spindle *b* is 10 driven through the medium of a suitable driving-pulley *B* with which it is preferably connected by means of a clutch-device indicated at *B'*, but not here illustrated in detail. The frame *A* is also constructed with bearings for a cam-shaft *c*, arranged below and parallel with the spindle *b* and adapted to be driven therefrom by suitable connections. As here shown the spindle *b* carries a pulley *B*² connected by a belt *b'* to a pulley *B*³, 20 which latter drives a train of gearing located in the housing *A'* and connected to rotate the cam-shaft *c*. These connections being well known and generally used in the winding art are not herein shown or described 25 in detail.

The cam-shaft *c* carries two cylindrical cams *C* and *C'* for reciprocating the two traverse-guides of the machine through connections as later described. The cam *C* 30 for the insulating-material-guide, called for convenience the thread-guide, is mounted fast on the shaft *c* and driven directly thereby through any suitable arrangement of key or spline, not here shown or described. 35 The cam *C'* for the wire-guide, on the other hand, is mounted free on the shaft *c* and driven independently thereof through separate means whereby it can be rotated at a much slower rate of speed than that of 40 the cam *C*. Any suitable arrangement may be employed for driving the cam *C'* from the spindle *b* independently of the cam *C*, such, for instance, as that described in the application for patent first referred to. As 45 here shown, however, the driving-connections between the spindle *b* and cam *C'* are of the type illustrated in my pending application for Patent, Serial No. 843,794, filed June 8, 1914. They consist essentially of 50 a worm-wheel *D* secured to the hub of the cam *C'* and adapted to be rotated from a worm or screw *d* on the vertical shaft *d'*. The shaft *d'* is driven from a train of gearing located in the casing *A*² at the top of 55 the machine and operated from a gear on the spindle *b*, these elements not being here shown in detail as they form no part of the present invention.

The winding-spindle *b* projects outwardly 60 beyond the end of the frame *A* and is adapted to receive a core or tube *x* on which the coil *W* is wound. Arranged on opposite sides of the projecting end of the spindle *b*, and adapted to be reciprocated longitudinally thereof, are the two traverse-guides

G and *G'*, see Fig. 2. The guide *G* for the insulating-material, hereinafter designated as the thread-guide, consists essentially of a hinged arm *g* adapted to slide on a horizontal rod *e* extending in parallel relation 70 to the spindle *b*. Preferably, the arm *g* is pivotally mounted on a bushing *g'* surrounding the rod *e* and connected to a downwardly-extending arm *F*. The lower end of the arm *F* is adapted to slide in a slot *e'* 75 in a rod *e*² arranged below and parallel with the rod *e*. The two rods *e*, *e*² are supported at one end in a bracket *E* secured to the end of the main frame *A* and their opposite ends are tied together by an arm or brace *E'*, 80 see Fig. 1. To the outer end of the guide-arm *g* are attached forked extensions *g*², *g*³ formed with notches through which the insulating-material or yarn *y* leads. Preferably, the lower branch *g*³ of the fork is 85 curled over at its end to provide a bearing-face which is adapted to rest on the surface on which the winding is being performed. Before leading through the notches at the ends of the forked extensions *g*², *g*³ the yarn 90 *y* passes over the edge of a trough-like guide *g*⁴ which is mounted on the bushing *g'*. The tension of the yarn drawing through the notches in the fork *g*², *g*³ tends to maintain the end of the guide-arm *g* normally bearing 95 against the surface of the winding, and as the coil increases in diameter the arm will swing upwardly on the pivot formed by the rod *e*.

The means for reciprocating the guide *G* 100 from its cam *C*, as here illustrated, consists essentially of an oscillating lever or rocker-arm *H* pivoted at *h* on an arm *E*², which forms an extension of the bracket *E*. On its lower arm the lever *H* carries a follower-stud or roll *h'* adapted to engage the groove *c'* in the periphery of the cam *C* while the upper arm of the lever is formed with a longitudinal slot *h*². The depending arm *F* which is attached to the thread-guide *G* 110 is also formed with a longitudinal slot *f* and connecting the two arms by means of their slots is a horizontal bar or link *J*. Preferably the fastening-means *j*—*j* at the ends of the link *J* are made adjustable up 115 and down in the slots *h*² and *f* so that the operative length of the rocker-arm *H* may be varied to alter its reciprocative effect on the guide *G*. In this way the extent of 120 traverse of the guide may be adjusted in accordance with the required length of the coil to be wound.

Referring now to the wire-guide *G'*, this has substantially the same arrangement of supporting and reciprocating means as the 125 guide *G*, and differs therefrom only in structural details. As illustrated in Fig. 2, two parallel, horizontal rods *k*, *k'* are supported at one end in a bracket *K* secured to the main frame *A*, while their outer ends are 130

5 tied together by a brace, not here shown, but similar to the arm E'. Mounted to slide on the rods k , k' is a vertical arm L, the lower end of which is connected to a hinged guide-arm g^5 . In this case the guide-arm g^5 is adapted to pivot about the axis of the lower rod k' and its upper end carries the guide proper G'. This consists essentially of a bracket g^6 formed with bearings 10 for two peripherally-grooved guide-wheels g^7 and g^8 . The wire w is arranged to lead down under the pulley g^7 and thence over the guide-wheel g^8 to feed it on to the spindle b. The tension of the wire tends to 15 maintain the guide-wheel g^8 in close relation to the surface of the winding and as the coil is built up in layers of increasing diameter the arm g^5 swings back on its pivot k' .

20 The wire-guide G' is reciprocated from the cam C' by means of the rockable lever M, similar in arrangement to the lever H, see Fig. 1, which is oscillated through the engagement of its stud m with the groove c^2 of the cam C'. Connecting the lever M with the sliding arm L is a link l, see Fig. 2, arranged in the same manner as the link J and also adjustable in position to vary the operative effect of the lever M.

39 The above described mechanism is of substantially the same construction and arrangement as that of the machines of the applications previously referred to. The essential novelty of the present improvement
35 resides chiefly in the form and arrangement of the traverse-cam C which reciprocates the thread-guide G. Heretofore, in machines of the type specified, it has been the practice to employ the same form of cam
40 for both the thread-guide and the wire-guide. That is to say, both cams were made of single throw to actuate both guides with a constant traverse extending first in one direction and then in the other. The cam
45 for the thread-guide is usually provided with a slightly longer throw than that of the cam for the wire-guide, but both cams have heretofore been arranged to give a constant extent of traverse and uniform speed of reciprocation to each guide. In my present improvement I now propose to employ an entirely different form of cam for reciprocating the thread-guide G whereby several additional reversals of movement are im-
50 parted to the guide at each end of its main traverse, and wherein the speed of reciprocation of the guide is also varied at certain predetermined intervals at the ends of its traverse. It is through this means that the
55 thread-guide G is caused to make what might be termed a halting or staggering motion at the ends of its main traverse whereby an increased amount of insulating-material or yarn is laid on the coil at these points.
60 To accomplish this purpose as above de-
65

scribed I employ a cam of an appropriate form such, for instance, as that illustrated in either Fig. 3 or Fig. 5. Fig. 3 shows the simplest form of cam adapted for the purpose intended, and Fig. 4 is a development 70 of the cam-groove with which the follower h' on the guide-reciprocating arm H engages. Preferably the cam C is of a type comprising a hub c^3 and radial spokes c^4 , c^4 supporting the relatively narrow, circular rim c^5 . Formed in the periphery of the rim c^5 is the slot or groove c' for the follower or stud h' as shown in development 75 in Fig. 4. Usually the groove c' extends approximately half way around the circumference of the cam for a complete traverse or throw in one direction, and the traverse is reversed around the other half of the circumference. This arrangement is variable, however, and the cam might be constructed with one throw to each quarter of its circumference or in accordance with other proportions. In Fig. 3 the improved cam shown is designed with its main throw in 80 each direction occupying slightly less than one half of its entire circumference and the remainder of its periphery is taken up by the shorter, supplementary traverses. This will be understood from the following explanation taken in connection with Fig. 4. 85 For instance, starting at the point t , which is the extreme of throw of the groove c' at one end of the cam, the main traverse of the groove extends at a predetermined pitch or lead to the opposite extreme at t' . At this 90 point the traverse of the groove is reversed to lead back in the opposite direction to t^2 . This reversal of the traverse is for a relatively short distance only, however, merely a small fractional part of the first or main 95 traverse from t to t' ; and at t^2 the groove c' again leads back in the opposite direction to the point t^3 which is on a line with the point t' . That is to say, from t' to t^2 and back to t^3 the groove c' is formed with a 100 short scallop or undulation having its straight portions connected by relatively long curves so as to provide for easy passage of the guiding stud or roll around the points of the cam. From the point t^3 the groove extends back in the opposite direction again in its main traverse leading to the point t^4 at the opposite end of the cam, and at this point the scallop or short traverse 105 is duplicated from t^4 to t^5 and back to t which is the starting point of its first, main traverse. 110

In Figs. 5 and 6 I have illustrated another type of cam having its groove formed with two extra undulations made by double reversals of the direction of its traverse. Starting at t^6 in Fig. 6, which is the extreme point of reversal of the main traverse at one end of the cam, the groove c' leads to t^7 at the opposite extreme of traverse; then

reverses for a short distance to t^8 , and back again to t^9 ; from t^9 it reverses once more to t^{10} , and back to t^{11} ; and thence to t^{12} in its long traverse to the opposite end of its throw 5 where the compounding is repeated before starting across from t^6 again in its first, long traverse. Stated briefly, each of the cams here illustrated has two primary traverses extending in opposite directions with a series of short traverses or undulations interposed between the main traverses. The action of the cam-grooves in traversing the thread-guide G will be best understood by reference to Figs. 7 and 8 of the drawings 10 which illustrate the central core or tube x of the coil W with one strand of yarn wound thereon in the convolutions which it makes in traversing from one end of the tube to the other and back again.

15 Referring first to Fig. 7, this shows a strand of yarn y , as traversed on the tube x by the thread-guide G operated from a cam of the form illustrated in Figs. 3 and 4. The dash-lines $w'-w'$, w^2-w^2 indicate the extent of traverse of the wire layers in this form of coil, see also Fig. 10, while the dot-and-dash lines $y'-y'$ and y^2-y^2 represent the extremes of traverse of the yarn-windings. In other words, W' represents the 20 length of the wire layers, while Y indicates the full traverse of the yarn-windings on the coil. As before stated, the yarn-windings overlap the ends of the wire layers and Y' therefore represents the thickness or width 25 of the abutments or closures of yarn to be built up at the ends of the coil. The course of the yarn in winding from one end of the coil to the other and back again is as follows: Starting at the point 3 the yarn y is 30 laid at a constant, predetermined pitch from one extreme of traverse y' to the opposite extreme y^2 . From the point 3 the yarn is shown on the front face of the tube x leading to the point 4, then around on the rear 35 face of the tube to 5, as illustrated by the dotted lines 6; from 5 back around the front face to 7; and thence rearwardly again to 8 which is the limit of its main traverse on the line y^2-y^2 . During the time the yarn 40 is making these convolutions on the tube x from y' to y^2 , the follower-roll or stud h' on the guide-reciprocating lever H will traverse the cam-groove c' , shown in Fig. 4, from t to t' and the winding-spindle b which carries the tube x will have made one complete 45 rotation and a fraction of another turn. This ratio between the speed of rotation of the winding-spindle and the reciprocation of the thread-guide can, however, be varied as 50 desired in accordance with the length of the coil being wound or other conditions. As here shown the yarn is wound with approximately one and one-quarter turns, or what is technically termed a one-and-one-quarter 55 "wind" for its main traverse from end to

end of the coil. The number of the "wind" best suited to any particular type of coil is usually determined by experiment based on the diameter of the wire, the size of the yarn, length and diameter of the coil and other 70 particulars.

After the thread-guide G has reached the end of its main traverse to bring the yarn y to the point 8 on the tube x , see Fig. 7, the shorter, supplementary portion of the cam-traverse comes into action and the resultant effect on the yarn is as follows: When the guide-actuating stud h' reaches the point t' of the cam-groove c' , shown in Fig. 4, the traverse of the guide G is reversed and the 75 yarn will now be laid at a less pitch or lead extending back from the point 8 in Fig. 7 to the point 9, which latter is on the line w^2-w^2 at the end of the wire traverse W' . That is to say, the cam C now acts to feed the guide 80 G back from the point 8 in the opposite direction, but instead of traveling it at the same rate of speed to lay the yarn in a reverse helix having the same pitch or lead as the first helix extending from 3 the speed of 85 the guide is retarded and the yarn is laid at a more obtuse angle to the axis of the tube x . This is caused by the change in the angle or pitch of the cam-groove c' between the points 90 t' and t^2 . When the guide-operating stud h' reaches the point t^2 the guide will be at 9 on the tube x and at this instant the reversal of throw of the cam causes the guide to traverse the yarn back again to the point 10 on the tube x . At this point the guide-reciprocating stud h' reaches the point t^3 on the cam C and the traverse of the guide is therefore once more reversed to carry it toward the opposite end of the tube x . That is to say, the main traverse of the cam-groove 100 from t^3 to t^4 now comes into action and the guide G is actuated to lay the yarn from the point 10, Fig. 7, to 11, thence to 12; from 12 to 13; and from 13 to 14 which is on the line $y'-y'$ at the extreme of the traverse in this 105 direction. At 14 the direction of traverse of the guide is once more reversed, through the action of the cam-groove at t^4 , and the yarn is given its supplementary traverse extending from 14 on the line $y'-y'$ to 15 on the line $w'-w'$ and then back again to 3 which is the starting point of its main traverse 110 from y' to y^2 . At this point the traverse of the thread-guide is reversed once more and the yarn is again led across the full length 115 of the coil between the limits $y'-y'$ and y^2-y^2 and the winding continues in the same manner as before described. In the meantime the wire-guide G' is being traversed by the cam C' at a constant rate of speed to lay 120 the wire in uniform layers extending from $w'-w'$ to w^2-w^2 as shown in Fig. 9, which is a view of the coil as nearly completed from the winding started in Fig. 7.

Fig. 10 illustrates a few layers of yarn 130

only wound onto the tube α in accordance with the method just described and shows the effect which this system has in building up the increased amount of yarn at the ends 5 of the layers. In the foregoing explanation no mention has been made of the fact that each succeeding helix laid along the tube α in either direction has a slight, circumferential advance or increment of lead 10 over the preceding helix extending in the same direction. This is effected through the proper adjustment of the ratio of speed between the thread-guide G and winding-spindle b and is a well known feature of the 15 Universal system of winding. Technically, it is known as the "gain", and the object is to provide that one turn or convolution of the yarn will make an advance or gain over the preceding turn to effect the side-by-side 20 laying of the strands in each layer. In winding wire coils with the present improved system it has been found expedient to exaggerate this gain in the lead of the yarn so that instead of laying the turns side-by-side 25 in close relation they are disposed at some little distance apart as shown in the central portion of the winding illustrated in Fig. 10. This results in a thinner layer of yarn between the wire layers and also provides a 30 better disposition of the reinforcing strands which pass between the turns of the wire. At the ends of the coil, however, the turns of yarn are laid with a closer wind which is preferable on account of giving a harder 35 and more solid formation. These last described features are merely technical details, however, and are not essential to an understanding of the principle of the invention. The main object of my improvement 40 is to provide means for disposing more insulating-material or yarn at the ends of the coil than between the wire layers in order to build more solid and compact end-abutments.

45 When the cam shown in Figs. 5 and 6 is employed in place of the one illustrated in Figs. 3 and 4 its action on the thread-guide G will have an effect on the laying of the yarn as follows: Referring to Fig. 8, the 50 yarn y will be laid from the starting point 16 in a convolution extending through the points 17, 18, 19 to 20 which is the limit of its main traverse. At this point the direction of movement of the thread-guide is reversed, as the stud h' reaches t^7 on the cam-groove c' , shown in Fig. 6, and the angle of lead of the yarn is also changed due to the change in pitch of the cam-groove. From 55 20 the yarn will be traversed back a short distance to 21, as the stud h' moves in the groove c' from t^7 to t^8 ; from 21 back to 22, as the stud h' moves from t^8 to t^9 ; from 22 back again to 23, see Fig. 8, while the stud moves from t^9 to t^{10} ; from 23 the yarn 60 leads back once more to 24 as the stud fol- lows from t^{10} to t^{11} ; and at this point the stud h' commences its long traverse from t^{11} to t^{12} to carry the guide back to the opposite end of the tube α . The yarn will therefore be laid from y^2 to y' in a convolution passing through the points 25, 26, 27 to 28 which is in line with its starting point. From 28 the yarn is laid with another series of short traverses leading to 29, and back to 30, thence back to 31, and once more back to 16, 70 as effected by the action of the undulating portion t^{12} , t^{13} , t^{14} and t^{15} of the cam-groove c' . It will be noted that in Fig. 8 the end traverses of the yarn y are shown as being shorter and of less pitch than those illustrated in Fig. 7. The reason for this is that the more traverses there are given to the yarn at the ends of the main traverse the faster it will build up and the more compact the yarn-mass will be. Therefore 75 where the yarn is laid with an increased number of short traverses the end abutments may be made thinner without sacrificing their firmness and stability.

80 The operation of the complete machine is 90 as follows: Power is applied to the driving-pulley B to rotate the winding-spindle b , and the cam-shaft c is driven therefrom through the medium of the belt b' connecting the pulleys B^2 and B^3 and operating the 95 train of gearing in the casing A' . The shaft c rotates the cam C and the stud or follower h' engaging with the groove c' acts to oscillate the rocker-arm H with first a long throw, next a series of shorter oscillations, 100 then a long stroke again, and so on. This peculiar, compound movement of the arm H is transmitted to the thread-guide G through the medium of the connecting-link J and sets up a corresponding reciprocating-motion consisting of relatively long traverses in each direction interrupted by a series of shorter, slower traverses at each end of the main traverse. The result of this compound 105 traverse motion of the thread-guide G is to 110 lay the yarn or other insulating-material on the tube or core α in the manner as previously described, so that it is built up with a more or less open wind throughout the greater portion of the length of the coil being produced, while at the ends of the coil the strands are laid more closely together in denser and more compact masses which form the end abutments or closures. Mean- 115 while, the wire-guide G' is being simultane- 120 ously reciprocated at a constant rate of speed, with a relatively slow, uniform traverse to dispose the wire w in close, spiral turns as illustrated in Fig. 9. The wire-guide G' receives its reciprocation from the 125 rocker-arm M which is oscillated by the cam C' turning free on the shaft c . As previously described, the cam C' is driven from the train of gearing located in the housing A^2 and connected with the spindle b . This 130

mechanism is usually provided with adjustable means for regulating the ratio of speed between the spindle and the wire-guide to provide for a proper spacing of the turns or convolutions of the wire in accordance with its thickness or diameter. The driving connections between the spindle *b* and cam *C* can also be adjusted to regulate the speed of the thread-guide *G* likewise, in consonance with the speed of rotation of the winding-spindle. The extent of traverse of both guides can be adjusted through the means previously described so that coils of various lengths, within certain prescribed limits, can be wound on the machine and the diameter of the coil can also be varied as required.

By reference to Figs. 9 and 10 it will be seen that with the method of winding effected through the use of my improved apparatus herein described the windings of insulating-material are caused to build up at a faster rate at the ends of the coil than in the layers intervening between the overlying turns of the wire, and in this way a better foundation for the wire-windings is provided. While, for the sake of clearness, I have here shown the yarn as being of approximately the same size as the wire, usually it is much finer and therefore would not build up as fast as the wire. With my present improvement the yarn can be built up in such a manner that it will form projecting shoulders at the ends of the layers as shown at y^3 in Fig. 10. These shoulders or ledges serve to hold the end turns of wire in place and prevent them from falling down over the edges of the coil. Furthermore the dense masses of insulating-material at the ends of the coil not only serve to reinforce its structure, but they also act to prevent short-circuiting of the current between the overlying end turns of the wire where the electrical potential is generally the greatest. In most cases where the yarn employed for insulation and reinforcement is very fine, I have found it expedient to wind it with the short traverses at the ends of the coil slightly overlapping within the ends of the wire layers. That is to say, instead of having the short traverses of the thread-guide confined to a space outside the limits of the wire layers, the inner end of each short yarn traverse is made to fall within the end of the wire traverse so that the yarn will be carried into the interstices at the ends of the wire layers and be thoroughly compacted into the structure at these points.

It is to be observed that the essential feature of my present improved winding machine is the means for reciprocating the thread-guide with a main or primary traverse of maximum length and for interrupting its uniformity of movement at the ends of this main traverse to set up a series

of shorter traverses whereby the guide is actuated with staggering motion at certain intervals of the winding. For accomplishing this effect I have preferred to herein describe and illustrate one embodiment of my invention in a machine employing a cam of peculiar form. It is obvious, however, that other forms of cams than those here shown could be used for the same purpose and it is also called to attention that other forms of traverse-motions could be employed in place of the cam. That is to say, a compound crank-motion might be substituted for the compound cam herein described, and other modifications in the traverse-mechanism might suggest themselves to those skilled in the art.

Various modifications could also be made in the structure and arrangement of the other parts of my improved apparatus without departing from the spirit or scope of the invention.

Therefore, without limiting myself to the exact embodiment shown and described, what I claim is:—

1. In a winding machine for winding electrical coils, the combination with a continuously rotating mandrel on which the conducting-material is wound, of a traverse-guide for winding insulating-material diagonally of the windings of conducting-material, and means to reciprocate said guide with a compound traversing-motion comprising primary traverses of uniform extent and shorter supplementary traverses occurring at either end of the primary traverses and maintained with a definite relation thereto.

2. In a machine for winding electrical coils, the combination with a continuously rotating mandrel on which the conducting-material is wound, of an oscillating traverse-guide for winding insulating-material diagonally of the windings of conducting-material having a main traverse of constant length extending between fixed limits and a supplementary traverse of less extent at both ends of the main traverse whereby the insulating-material is built up at a faster rate at the ends of the coil than between the layers of conducting-material.

3. In a machine for winding electrical coils, the combination with a continuously rotating mandrel for receiving the turns of wire to be wound thereon, of a traverse-guide for winding insulating-material diagonally of the wire-windings, and means to reciprocate the guide with a constant extent of traverse between fixed limits and to also impart to the guide a series of shorter supplementary traverses occurring at the completion of each main traverse and having a definite relation thereto.

4. In a machine for winding electrical coils, the combination with a continuously

rotating mandrel, of means to wind wire on said mandrel in a series of superimposed layers, and means to traverse insulating-material diagonally with respect to the wire-windings across the full length of the layers thereof and to impart a series of supplementary traverses to the insulating-material at the ends of the wire layers to build the material up in abutments to reinforce the ends

10 of the coil.

5. In a machine for winding electrical coils, the combination with a continuously rotating mandrel for receiving the layers of wire-windings disposed in closely adjacent turns extending between fixed limits, of a traverse-means for winding insulating-material diagonally of the coils of wire-windings and across the full length thereof, and means for operating said traverse-means with a main traverse equal to the length of the wire layers and supplementary shorter traverses arranged outside the limits of the main traverse and occurring at regular intervals at the completion of 25 each main traverse.

6. In a machine for winding electrical coils, the combination with a continuously rotating winding-spindle for receiving the wire-windings disposed in layers thereon, of a reciprocating traverse-guide for insulating-material, and means to reciprocate said guide longitudinally of the spindle with first a relatively long traverse, next a series of shorter traverses, then a long traverse in 35 the opposite direction, then a series of short traverses again with the said compound traversing-motion continued progressively throughout the whole operation of the machine and with the long traverse maintained 40 between fixed limits and the shorter traverses having a definite and constant relation thereto.

7. In a machine for winding electrical coils, the combination with a continuously 45 rotating winding-spindle for receiving the wire-windings disposed in layers thereon, of a reciprocating traverse-guide for winding insulating-material simultaneously with the winding of the wire, and means to reciprocate the guide with a compound traversing-motion consisting of primary traverses of uniform extent extending between fixed limits and supplementary traverses of less extent at the ends of the primary traverses 55 and bearing a constant relation thereto with the shorter traverses made at a slower rate of speed than that of the long traverses.

8. In a machine for winding electrical coils, the combination with a continuously 60 rotating winding-spindle for receiving the layers of conducting-material to be wound thereon, of a traverse-guide for insulating-material adapted to be traversed longitudinally of the spindle, and means to operate 65 said guide with a compound traversing-mo-

tion consisting of primary traverses of uniform extent made at a predetermined rate of speed with respect to the speed of rotation of the winding-spindle, and shorter supplementary traverses at the ends of the primary traverses having a constant relation thereto, said supplementary traverses made with the guide operating at a reduced rate of speed.

9. In a machine for winding electrical 75 coils, the combination with a rotating winding-spindle, of means for guiding conducting-material to dispose it in layers on the spindle, means for guiding insulating-material across the layers of windings of conducting-material, and means to cause a compound reciprocating motion between the spindle and guiding-means for the insulating-material to cause the latter to be laid with a main traverse equal to the full extent of the layers of conducting-material and supplementary traverses of shorter length falling outside of the main traverse and serving to build the insulating-material in compact abutments supporting the ends 85 of the coil.

10. In a machine for winding electrical coils, the combination with a rotating winding-spindle, of means to traverse wire longitudinally of the spindle to dispose it in 95 layers of close-wound turns, a guide for insulating-material, and means to traverse said guide across the full extent of the wire layers and to impart a supplementary series of traverses thereto at the ends of the main traverse to cause the insulating-material to be built up in abutments for reinforcing the ends of the coil.

11. In a winding machine, the combination with a rotating winding-spindle and a reciprocating traverse-guide, of a compound cam having a continuous operating face for reciprocating the guide with a primary traverse of predetermined extent interrupted by a series of shorter supplementary reverse 110 traverses at each end of the primary traverse.

12. In a winding machine, the combination with a rotating winding-spindle, of a reciprocating traverse-guide, a cam formed with a continuous cam-face formed with 115 throws of maximum and minimum extent, and means to connect the guide to be reciprocated from the cam with a primary traverse of maximum extent and shorter traverses of less extent.

13. In a winding machine, the combination with a rotating winding-spindle, of means for traversing wire longitudinally of the spindle, a traverse-guide for insulating material also adapted to be traversed longitudinally of the spindle, an oscillating lever connected with the insulating material guide to traverse the latter, means to adjust the guide connection on the lever to vary the operative effect thereof, and means to oscillate 125 130

the lever with a primary movement of maximum extent followed by a series of supplementary oscillations of less extent.

14. In a winding machine, the combination with the rotating winding-spindle, of a traverse-guide, an oscillating lever for traversing the guide, a cam-follower on the lever, and a compound cam formed with a continuous cam-face with which the follower 10 engages, said cam-face having primary throws of maximum extent leading in opposite directions and interrupted by supplementary reverse throws of less extent intervening between and connecting the primary 15 traverses.

15. In a winding machine, the combination with the rotating winding-spindle, of a traverse-guide adapted to be reciprocated longitudinally of the spindle, and a cam for 20 reciprocating the guide, said cam having a continuous cam-face formed with primary throws of equal extent extending in opposite directions and supplementary reverse traverses of shorter throw formed by undulations 25 of the cam-face intervening between and connecting the ends of the primary traverses.

16. In a winding machine, the combination with the rotating winding-spindle, of a 30 traverse-guide adapted to be traversed longitudinally of the spindle, and a cam for reciprocating the guide formed with a follower-groove having portions extending angularly in opposite directions and interrupted by shorter undulatory portions connecting the ends of the angular portions of 35 the groove in the manner and for the purpose described.

17. In a winding machine, the combination 40 with the thread-guide, of a cam for traversing the guide, said cam formed with helically disposed cam-faces extending in opposite directions, and interrupted by a plurality of shorter undulatory reverse faces 45 connecting the ends of the main helical faces of the cam.

18. In a winding machine, the combination 50 with the traverse-guide, of a cam for traversing the guide, said cam formed with a guiding-groove on its periphery having compound traverses consisting of helical portions extending in opposite directions and interrupted by relatively shallow undulations connecting and interposed between 55 the helical portions of the groove.

19. In a winding machine, the combination 60 with the rotating winding-spindle, of a plurality of traverse-guides adapted to be simultaneously reciprocated longitudinally of the spindle, and means to reciprocate one of the guides, with a compound traversing motion consisting of primary traverses of

maximum extent extending in opposite directions and supplementary reverse traverses of less extent intervening between the primary traverses. 65

20. In a winding machine, the combination with a rotating winding-spindle, of a plurality of traverse-guides adapted to be traversed axially of the spindle, and means 70 to actuate one of the guides with a longer traverse than that of the other guide and with its traversing-motion compounded to effect a primary traverse of maximum extent in opposite directions and supplementary traverses of less extent at each end of the primary traverse. 75

21. In a coil-winding machine, the combination with a rotating winding-spindle, of a guide for traversing the wire on the 80 spindle, a second traverse-guide for winding insulating-material into the coil, and means to traverse the insulating-material-guide with a compound motion consisting of primary traverses extending the length of the 85 coil and shorter supplementary traverses at both ends of the coil.

22. In a coil-winding machine, the combination with a rotating mandrel for supporting the coil, of a wire-guide for directing the conducting-material onto the mandrel, means to traverse the wire-guide to lay the conducting-material in uniform layers of spiral turns, a thread-guide for traversing insulating-material diagonally of the wire-windings, and means to operate the thread-guide with a compound traversing-motion consisting of primary traverses extending the length of the wire layers and shorter supplementary traverses at the ends of the 100 primary traverses acting to build up abutments of insulating-material at the ends of the coil. 90

23. In a machine for winding coils for electrical purposes, the combination with a rotating mandrel for supporting the coil, of a traverse-guide for the conducting-material, means to traverse said guide to dispose the conducting-material in layers of spiral turns, a traverse-guide for insulating-material, and means to operate the last named guide to traverse the insulating-material diagonally of the wire-windings and to effect a series of short traverses at the ends of its main traverse to build up a greater mass of insulation at the ends of the coil than between the layers. 105

In testimony whereof I affix my signature in presence of two witnesses.
